UNITED STATES PATENT OFFICE

102,179

DESIGN FOR A MOTOR VEHICLE HEAD LAMP ATTACHMENT OR SIMILAR ARTICLE

Harold B. Donley, Columbus, Ohio, assignor to
Columbus Metal Products Inc., Columbus, Ohio,
a corporation of Ohio

Application September 15, 1934, Serial No. 53,295

Term of patent 7 years

To all whom it may concern:

Be it known that I, Harold B. Donley, a citizen of the United States, residing at Columbus, in the county of Franklin and State of Ohio, have invented a new, original, and ornamental Design for a Motor Vehicle Head Lamp Attachment or Similar Article, of which the following is a specification, reference being had to the accompanying drawing, forming a part thereof.

Fig. 1 is a perspective view of the motor ve-

hicle head lamp attachment or similar article showing my new design;

Fig. 2 is a top plan view thereof;
Fig. 3 is a rear elevation thereof.

I claim:

The ornamental design for a motor vehicle head lamp attachment or similar article, as shown.

HAROLD B. DONLEY.
